NATHANIEL A. BOYNTON, OF NEW YORK, N. Y.

Letters Patent No. 98,915, dated January 18, 1870.

BASE-BURNING STOVE.

The Schedule referred to in these Letters Patent and making part of the same.

To all whom it may concern:

Be it known that I, NATHANIEL A. BOYNTON, of the city, county, and State of New York, have invented a new and useful Improvement in Base-Burning Stoves; and I do hereby declare the following to be a full, clear, and exact description thereof, which will enable those skilled in the art to make and use the same, reference being had to the accompanying drawing, forming part of this specification, in which drawing—

Figure 1 is a vertical central section of my improved stove.

Figure 2 is a horizontal section.

Similar letters indicate corresponding parts.

This invention is adapted, particularly, to that class of base-burning or reservoir-stoves known as fire-place stoves or heaters, and to other reservoir-stoves which have only a part of their exterior surfaces exposed to view, as where they are set in a fire-place or recess, or near to a wall, so that there is only a narrow space left behind the stove.

This invention consists in so connecting the reservoir of a base-burning stove with the fire-pot, that the combustion-chamber is, in part, shut off from the fire.

The letter A designates the exterior wall or cylinder of a base-burning fire-place stove.

The cylinder A contains a fuel-reservoir, B, which has close sides, and is fitted in the stove, and hung centrally and perpendicularly, one part or side of which may be connected, at its lower edge, with, and partially supported by, the wall or lining of the fire-pot, while the rest is disconnected, and is suspended above the grate.

Between the reservoir B and the cylinder A, is an annular space, D, commonly called a combustion-chamber, into which enter the hot gases and products of combustion from the fire.

I have found in stoves of this class, when made with the reservoir suspended entirely free, and disconnected from the fire-pot, (as now constructed,) and set in a fire-place or recess, where some parts are enclosed or confined therein, that the reservoir, at the place opposite or adjoining to the confined parts, is liable to be burned out, while the rest of the reservoir, opposite or adjoining to those parts of the stove which are exposed to the air of the room, remains unimpaired. I attribute this result to the confinement of such retired parts of the stove, in which position they cannot radiate their heat freely out into space, as is the case with the unconfined parts of the stove; while the generation of heat is as active in such confined parts of the stove as in the unconfined parts, the gases and products of combustion from the fire entering the combustion-chamber on all sides alike, to as great a degree on the

side where the radiation is slow or inactive as on the side where it is active.

It is true, that in fire-place heaters, the outer air has access to the confined part of the stove, in order that it may become warmed before it is allowed to ascend to distant apartments, but this circumstance does not prevent the evil, perhaps because the incoming air is not sufficient in quantity to carry off the excess of heat.

This injury could be prevented by moving the stove out to an open position, where all parts of the stove would be equally liable to part with heat by radiation, but to do this would be to do away with fire-place stoves.

My invention overcomes the difficulty, without interfering with the proper function of the stove as a fire-place stove or heater.

In carrying out my invention, I connect the bottom edge of the fuel-reservoir B with the fire-brick or lining of the fire-pot, along the part which is opposite to the confined or enclosed portion of the stove, so as to close the bottom of the combustion-chamber, or annular space D, along that portion. This connection is marked E, and, in this example of my invention, I have made it by thickening the wall or lining F, of the fire-pot, at that place, causing it to project inward for the distance required, until it comes under the edge of the reservoir, so that the rear part of the reservoir and the rear part of the fire-pot become connected, and form continuations of each other, so as to prevent the gases and flame going from the back part of the fire directly into the back part of the combustion-chamber D, and to cause said gases and flame to be deflected toward those parts of the combustion-chamber which are in front of the connection E, thereby causing the most active combustion to take place forward of the confined part of the stove, and relieving such confined part from being heated to the same degree as the uncovered parts.

It may not at all times be convenient to make this joint absolutely air-tight, but it is intended to make the connection between the bottom of the reservoir, and its point of junction with the lining, practically close.

What I claim as new, and desire to secure by Letters Patent, is—

The connection E, of the reservoir B, in base-burning stoves, with the fire-pot F, substantially as described, whereby the combustion-chamber D is shut off from the fire.

N. A. BOYNTON.
